DELTA WING INFLATABLE KITE

Julius M. Christoffel, Jr., Houston, Tex., assignor to
Gayla Industries, Inc., Houston, Tex.

Filed Sept. 28, 1972, Ser. No. 292,873

Term of patent 14 years

Int. Cl. D21—01
U.S. Cl. D34—15 AF

FIG. 1

FIG. 2

FIG. 3

FIG. 4

FIG. 1 is a perspective view of a kite from bottom side, in inflated condition;

FIG. 2 is a bottom plan view of the kite shown in FIG. 1;

FIG. 3 is a side view of the kite shown in FIGS. 1 and 2;

FIG. 4 is an elevational view from the tail of the kite shown in FIGS. 1-3.

I claim:

The ornamental design for a delta wing inflatable kite, as shown.
